SILVER CLEANING DEVICE

Burton L. Chase, Dallas, Tex.

Application August 18, 1947, Serial No. 769,179

1 Claim. (Cl. 204—271)

1

This invention relates to devices for removing tarnish from silver and more particularly to a device for cleaning silverware electrolytically.

The principal object of the invention is to provide a silver cleaning device consisting of a pair of parallel metallic plates separated by an insulating medium which closes the space between them to preclude the likelihood of short-circuiting by articles to be cleaned. By virtue of suitable electrode leads attached to the plates, current may be supplied to the plates while the device is submerged in a suitable electrolytic solution contained in a vessel. In this manner, tarnish may be removed from silverware without sacrificing the silver plate which usually occurs when abrasive or scouring agents are employed.

Another object of the invention is to provide a simple device especially useful to housewives for cleaning silverware since the device operates on low voltage and may be used with an electrolyte consisting of soapy water or other simple home prepared composition of suitable nature.

With the foregoing objects in view, the invention has further reference to certain features of accomplishment which will become apparent as the description proceeds, taken in connection with the accompanying drawing wherein:

Figure 1 is a perspective view of the invention.

Figure 2 is a side elevational view partly in section showing the silver cleaning device submerged in an electrolytic solution, and

Figure 3 is a view in vertical section.

Continuing with a more detailed description of the drawing, reference numeral 10 denotes a flat metal bottom plate separated from a top plate 11 by an insulator 12, the latter completely enclosing the space between the plates in order to exclude small articles such as spoons 13, knives, forks and the like to prevent short circuiting the plates 10 and 11.

It is obvious that the plates 10 and 11 can be of any desired size and shape and in order that the space between the plates may fill with electrolytic solution in which the device is submerged, a series of small apertures 14 are provided in the top plate 11.

Attached to the plate 10 is an electrode lead consisting of a stationary lower section 15, to which is hinged at 16, an upper section 17. Similarly, a stationary lead 15a is affixed to plate 11 to which is attached, by means of hinge 16a, an upper section 17a. For convenience in handling, these electrode leads are made in section so that the upper sections thereof may be folded into parallelism with the top plate 11, as shown in 55

Figure 1. The device is made more compact through the collapsibility of the electrode leads permitting the same to be conveniently packaged for shipping and storage.

To remove tarnish from silver, a suitable electrolytic solution 18 is placed in a vessel 19 and the described device is submerged in the solution, as shown in Figure 2. A wire 20 is attached to each of the electrode leads 17 by suitable clamps, not shown. Voltage is reduced in the wires 20 by a transformer 21 to remove any possible hazard and the articles to be cleaned are placed on the top plate 11 in the solution 18. After current is turned on, it requires but a very short time to remove the tarnish from the submerged articles.

Manifestly, the construction as shown and described is capable of some modification and such modification as may be construed to fall within the scope and meaning of the appended claim is also considered to be within the spirit and intent of the invention.

What is claimed is:

In a device for removing tarnish from silverware, the combination comprising a vessel containing an electrolytic solution, a pair of relatively parallel, horizontal, disc electrodes submerged in the electrolytic solution in said vessel, the upper of said electrodes is perforated and adapted to support said silverware, an annular spacing member of insulating material interposed between said electrodes adjacent the perimeter thereof to preclude entrance therebetween of articles of silverware, an electrode lead in hinged sections attached to each of said electrodes and adapted to be folded inoperatively onto the said upper electrode, and means for circulating low voltage electrical current through said electrodes and said electrolytic solution.
